US00D911098S

(12) **United States Design Patent** (10) **Patent No.:** **US D911,098 S**
Thurin et al. (45) **Date of Patent:** **** Feb. 23, 2021**

(54) **CONTAINER LID**

(71) Applicant: **S.C. Johnson & Son, Inc.**, Racine, WI (US)

(72) Inventors: **Matthew N. Thurin**, Wauwatosa, WI (US); **Rishabh Singh**, Milwaukee, WI (US); **Christopher M. Wlezien**, Chicago, IL (US); **Peter I. Capraro**, San Francisco, CA (US); **Allan Freas Velzy**, Boston, MA (US)

(73) Assignee: **S. C. Johnson & Son, Inc.**, Racine, WI (US)

(**) Term: **15 Years**

(21) Appl. No.: **29/660,325**

(22) Filed: **Aug. 20, 2018**

Related U.S. Application Data

(63) Continuation of application No. 29/613,227, filed on Aug. 8, 2017, now Pat. No. Des. 829,545, which is a continuation of application No. 29/535,311, filed on Aug. 5, 2015, now Pat. No. Des. 797,552, which is a continuation of application No. 29/461,259, filed on Jul. 19, 2013, now Pat. No. Des. 741,171, and a continuation of application No. 29/461,254, filed on Jul. 19, 2013, now Pat. No. Des. 742,224, and a continuation of application No. 29/461,255, filed on Jul. 19, 2013, now Pat. No. Des. 752,973, and a continuation of application No. 29/461,250, filed on Jul. 19, 2013, now Pat. No. Des. 741,170, and a continuation of application No. 29/461,258, filed on Jul. 19, 2013, now Pat. No. Des. 744,336, and a continuation of application No. 29/461,252, filed on

(57) **CLAIM**

The ornamental design for a container lid, as shown and described.

DESCRIPTION

FIG. 1 is a top perspective view of a container lid showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the Figures show portions of the container lid which form no part of the claimed design.

1 Claim, 7 Drawing Sheets

Related U.S. Application Data

Jul. 19, 2013, now Pat. No. Des. 750,483, and a continuation of application No. 29/469,505, filed on Oct. 10, 2013, now Pat. No. Des. 741,708, and a continuation of application No. 29/469,506, filed on Oct. 10, 2013, now Pat. No. Des. 742,743, and a continuation of application No. 29/484,860, filed on Mar. 13, 2014, now Pat. No. Des. 760,073.
